E. S. HESS.

REFINISHER.

APPLICATION FILED APR. 1, 1922.

Patented Oct. 3, 1922.

WITNESS

P. F. Dilworth

INVENTOR.

Edwin S. Hess
BY *Edward A. Lawrence*,
his ATTORNEY

Patented Oct. 3, 1922.

UNITED STATES PATENT OFFICE.

EDWIN S. HESS, OF BELLEVUE BOROUGH, PENNSYLVANIA.

REFINISHER.

Application filed April 1, 1922. Serial No. 548,701.

To all whom it may concern:

Be it known that I, EDWIN S. Hess, a citizen of the United States, and residing in the borough of Bellevue, in the county of Allegheny and State of Pennsylvania, have 5 invented or discovered the new, useful, and Improved Refinisher, of which the following is a specification.

My invention consists in a new and improved implement for treating and refinishing textiles and the like.

The object which I have in view is the provision of an implement which may be used to bring out or restore the nap of cloth and other textiles; to restore the fluffiness of blankets and the like after washing or cleansing; for removing larvae and other foreign matter from furs, and for similar purposes.

Generally speaking my invention consists of a hand implement which may be conveniently used for these purposes in the home or shop.

In its preferred form it comprises a sheet metal implement whose working face is provided with barbs, preferably struck from the metal, of varying fineness. Thus I prefer to provide coarser barbs to abrade the threads of a garment worn smooth and shiny, and finer barbs to comb the new nap produced by abrasion and remove loose material, and I also prefer to provide a smooth, unbarbed portion to smooth the combed nap.

The coarser barbs are preferably so disposed with relation to the finer barbs that when the implement is moved over the surface of the cloth, the coarser barbs are in advance so that the formation of the new nap, its combing and its smoothing are progressively accomplished as the implement is used. However, I provide such a relative disposal of the barbs that by moving the implement in a direction transverse to that above described, the coarse barbs will engage the cloth for substantially the full extent of the implement.

In the accompanying drawings, which illustrate a convenient and advantageous embodiment of the principles of my inven-

tion; Fig. 1 is a face view of the same; Fig. 2 is a longitudinal section of the same; Fig. 3 is a transverse section of the same, and Fig. 4 is an enlarged detail showing the manner of producing the coarser and finer barbs.

The following is a detailed description of the drawings.

The instrument is formed of a piece or blank of sheet steel, bent up in hollow form having its front end tapered to a relatively sharp point. The edges of the metal overlap along the back of the implement and may be soldered or welded together. The front or working face of the implement is provided with two characters of barbs, coarser barbs 1 and finer barbs 2. These barbs may be conveniently formed by punching out the metal, as better shown in Fig. 4. The coarser barbs extend from the front or pointed end of the instrument toward its base, while the finer barbs are located near the base of the instrument, and preferably in the manner shown, covering a triangular space with its base toward the base of the instrument and extending for substantially the full width of the instrument. Thus at the side edges of the instrument the coarser barbs extend for nearly its full length. The base extremity of the instrument is preferably occupied by the transversely disposed plane, smoothing portion 3, which is preferably slightly below the level of the barbs, so that when the latter are sunk into the cloth the plane portion 3 will travel over the surface of the cloth.

When used for refinishing worn cloth, the implement is moved over the surface of the cloth with the pointed end foremost, the coarser barbs first engaging the cloth and abrading its threads to form a new nap, which new nap is next engaged by the finer barbs which comb the same and remove any loose material, and the plane surface then passes over and smooths the combed nap.

When the implement is to be used, for instance, to bring out the nap of carpet or rugs, instead of being moved with its pointed end at the front, it is moved laterally or in a direction transverse to that above described, so that the coarser barbs engage the

50

carpet for the full extent of the implement. To enable the instrument to be used conveniently I provide its back with the looped handle 4.

5 I have found the implement of great advantage, being enabled therewith to refinish with a new and most satisfactory nap, garments which have worn smooth and shiny from years of use. The provision of the 10 sharply pointed end enables the implement to be worked in between and around buttons, trimmings and the like.

15 I have also found the implement of great advantage for renovating furs, the fur being freed from larvae of moths and from other insects, and the smoothness and gloss being entirely restored.

What I desire to claim is:—

20 1. An implement for the purposes described provided on its working face with 25 barbs, said barbs being arranged according to different degrees of fineness in such a manner that when the implement is passed over the surface of cloth the coarser barbs first abrade the threads to form a new nap and the finer barbs then comb the nap and remove loose material.

30 2. An implement for the purposes described provided on its working face with 35 barbs, said barbs being arranged according to different degrees of fineness in such a manner that when the implement is passed over the surface of cloth the coarser barbs first abrade the threads to form a new nap and the finer barbs then comb the nap and remove loose material, and said implement being further provided with a plane portion following the finer barbs to smooth the combed nap.

40 3. An implement for the purposes described provided with a working face of triangular form, the apex of the working face being provided with coarser barbs for abrading the threads of cloth to form a new nap while the base of said face is provided with finer barbs for combing the new nap and removing loose material.

45 4. An implement for the purposes described provided with a working face of 50 triangular form, the apex of the working face being provided with coarser barbs for abrading the threads of cloth to form a new nap while the base of said face is provided with finer barbs for combing the new nap and removing loose material, and said implement being further provided with a plane portion following the finer barbs to smooth the combed nap.

55 5. An implement for the purposes described provided on its working face with 60 barbs, said barbs being arranged according to degrees of fineness whereby by passing the implement in the proper direction over the surface of cloth the coarser barbs 65 abrade the threads of the cloth to form a

new nap while the finer barbs follow to comb the new nap and remove loose material, the coarser barbs being extended down alongside of the finer barbs so that when the implement is moved over material in a direction transverse to that above described the coarser barbs will engage for substantially the full extent of the implement. 70

6. An implement for the purposes described provided on its working face with 75 barbs, said barbs being arranged according to degrees of fineness whereby by passing the implement in the proper direction over the surface of cloth the coarser barbs abrade the threads of the cloth to form a new nap 80 while the finer barbs follow to comb the new nap and remove loose material, the coarser barbs being extended down alongside of the finer barbs so that when the implement is moved over material in a direction transverse to that above described the coarser barbs will engage for substantially 85 the full extent of the implement, and said implement being provided in the rear of the finer barbs with a plane portion to smooth 90 the combed nap.

7. An implement for the purposes described produced by bending up a sheet of metal into hollow form with a working face tapered toward one end, the working face 95 of said implement being provided with barbs by punching out the metal.

8. An implement for the purposes described produced by bending up a sheet of metal into hollow form with a working face 100 tapered toward one end, the working face of the implement being provided with barbs by punching out the metal, the barbs adjacent to the tapered end being coarser than those adjacent to the other end of said implement. 105

9. An implement for the purposes described produced by bending up a sheet of metal into hollow form with a working face tapered toward one end, the working face of 110 the implement being provided with barbs by punching out the metal, the barbs adjacent to the tapered end being coarser than those adjacent to the other end of said implement, and the last named end of said implement being provided with a plane portion 115 for the purpose described.

10. An implement for the purposes described produced by bending up a sheet of metal into hollow form tapered to a point 120 at one end, the working face of said instrument being provided with punched out barbs, the barbs toward the tapered end of said implement being coarser than those toward the butt end of said implement, but 125 said coarser barbs being extended alongside of the finer barbs toward the butt end of said implement.

11. An implement for the purposes described produced by bending up a sheet of 130

metal into hollow form tapered to a point at one end, the working face of said instrument being provided with punched out barbs, the barbs toward the tapered end of 5 said implement being coarser than those toward the butt end of said implement, but said coarser barbs being extended alongside of the finer barbs toward the butt end of said implement, and the butt end of said implement being provided with a plane 10 smooth portion for the purpose described.

Signed at Pittsburgh, Pa., this 29th day of March, 1922.

EDWIN S. HESS.
